UNITED STATES PATENT OFFICE.

WILLIAM J. FRANCKE, OF NEW BRUNSWICK, NEW JERSEY.

ROTARY CUT-OFF VALVE.

SPECIFICATION forming part of Letters Patent No. 726,419, dated April 28, 1903.

Application filed November 15, 1902. Serial No. 131,473. (No model.)

To all whom it may concern:

Be it known that I, WILLIAM J. FRANCKE, a citizen of the United States, residing in New Brunswick, in the State of New Jersey, have 5 invented certain new and useful Improvements in Rotary Cut-Off Valves, of which the following is a specification, reference being had to the accompanying drawings, forming a part hereof.

10 This invention relates to valves which rotate continuously in one direction and are therefore particularly adapted for use in connection with high-speed engines.

The general object of the invention is to 15 improve the construction of valves of this class so that they shall operate more satisfactorily at very high speed and shall be capable of easy regulation or adjustment to meet varied conditions of use. In a valve 20 constructed in accordance with the invention the cut-off can be changed without changing the lead and the cut-off, the lead, the release, and the compression can each be changed independently of the others. Furthermore, the 25 parts are so constructed and related that the valve is practically a balanced valve.

Other features of the improved valve will 30 be pointed out more particularly hereinafter with reference to the accompanying drawings, 30 in which the invention is illustrated in different embodiments.

In the drawings, Figure 1 is a vertical central section of a two-cylinder single-acting engine to which the improved valve is applied. 35 Fig. 2 is a vertical central section on a plane at right angles to that of Fig. 1. Fig. 3 is a horizontal section on the irregular plane indicated by the line 3 3 of Figs. 1 and 2. Fig. 4 is a view similar to Fig. 1, but illustrating 40 the application of the valve to a single-cylinder double-acting engine. Figs. 5 and 6 are sections on the planes indicated by the lines 5 5 and 6 6, respectively, of Fig. 4. Fig. 7 is a vertical central section showing on the same 45 scale the outer shell or casing and the fixed sleeve shown in Fig. 4, the plane of the section being at right angles to the plane of section of Fig. 4.

Although the present invention is not concerned with the particular construction of the engine with which it is employed, so much of the engine as is necessary to enable the ap-

plication of the invention to be clearly understood is shown in Figs. 1, 2, and 3. In the structure there represented the crank-shaft A, mounted in suitable bearings, has coupled to its cranks two single-acting trunk-pistons B, which reciprocate in their respective cylinders C. Between the cylinders C is disposed the valve-gear common to both. 55 The valve is actuated by a shaft mounted in suitable bearings in the frame or casing and driven continuously in one direction by bevel-gears d from the crank-shaft A. One section D of the valve-shaft has no longitudinal movement, while the other section D' is arranged to have longitudinal movement while rotating with the section D, an ordinary coupling (indicated at d') being provided to permit the longitudinal movement of one section, while 60 insuring the rotation of both sections together. The section D' is arranged to be moved longitudinally by the engine-governor E, which may be of ordinary or preferred construction and need not be further described herein. As the 65 valve, however, is exceedingly sensitive, it may be desirable in some cases to make the governors somewhat stiffer in action by making the balls e somewhat heavier than usual and by interposing between the movable governor-head e' and the rotating but longitudinally-immovable ring e² one or more springs e³, to be overcome by the action of the balls as they 70 respond to increased speed of the engine. The shaft-section D' has mounted thereon to 75 rotate and to move longitudinally therewith a sleeve F, the connection between the sleeve and the shaft being effected in the construction shown in Figs. 1, 2, and 3 by an arm f, and said sleeve is provided on one side with 80 a supply-port f' and on the other side with an exhaust-channel f². Within the rotating sleeve F is a non-rotating sleeve G, which in the construction now referred to may be formed integral with the outer shell or casing, so that it neither rotates nor moves longitudinally. It is provided with a port or 85 ports g and with a port g' in this case at its end, which communicates with the steam-inlet g². Outside of the rotating sleeve F is 90 a fixed sleeve H, which is in effect a part of the shell or casing K and is provided with ports h and is in communication through its open end h' with the exhaust I. The cylin- 95 100

der supply and exhaust port *c* is adapted for communication with the ports *h*.

In the operation of the form of the valve already described as applied to a two-cylinder single-acting engine, as represented in Figs. 1, 2, and 3 of the drawings, the steam enters the fixed sleeve *G* through the steam-inlet port *g'* and passes thence through the port *f'* of the rotating sleeve *F* and the obliquely-disposed port *h* of the fixed sleeve *H*, which for convenience is formed independently of the valve shell or casing *K*, into the port *c* of the cylinder *C*, behind the piston therein. As will be understood, the end of the sleeve *G* is closed and has a snug fit within the sleeve *F* and around the shaft *D'* or a bushing *d'*, which is interposed between the shaft and the sleeve. While steam is admitted to one cylinder, as just described, the exhaust-steam from the other cylinder passes through the port *c* and the port *h* of the sleeve *H* and the open end *h'* of the sleeve *H* to the exhaust-outlet *I*. As the sleeve *F* rotates with the shaft-section *D'* steam will be admitted through ports *h* and *c* behind the piston the instant that the port *f'* overlaps the end of the port *g* in the sleeve *G*, and the lead consequently will not be varied; but as the sleeve *F* is moved longitudinally by the action of the governor *E* the position of the port *f'* with respect to the obliquely-disposed port *h* in the sleeve *H* will vary with the speed of the engine, so that the cut-off will be varied, while the lead remains unchanged. The port *g* in the sleeve *G* is long enough to be overlapped by the port *f'* in whatever position the sleeve *F* may be, and as its position with respect to the port *h* is unchanged by the rotation of the sleeve *F* steam will always be admitted to the cylinder at the same point with relation to the position of the piston without regard to the shifting of the cut-off through the longitudinal movement of the sleeve *F*. The cut-off of course is always determined by the action of the governor. The lead can be determined to suit the requirements of the particular engine by rotating the sleeve *F* slightly forward or backward with reference to the crank-shaft and therefore with reference to the pistons, such rotation of the sleeve *F* being permitted by loosening the set-screw *d'* by which the shaft *D* is secured in the corresponding beveled gear *d*. Release and compression can also be determined for each engine by cutting away more or less one edge or the other of the exhaust-channel *f*² in the sleeve *F*.

Although the valve has been shown and described as applied to a two-cylinder single-acting engine, it will be readily understood that with slight modification it can also be applied to a single-cylinder double-acting engine. Such an application of the valve is represented in Figs. 4, 5, 6, and 7. The principal change is in the arrangement of the parts to permit steam to be admitted to the

central portion of the sleeve *G* and to be delivered therefrom to the opposite ends of the cylinder *C* alternately. To accomplish this, two sleeves *F'* and *F*², similar to the sleeve *F* in the construction previously described and similarly provided with ports *f'*, but oppositely placed, are secured upon the shaft-section *D'*. The sleeve *G'* is likewise similar to the sleeve *G* of the construction previously described, but is provided at each end with a port *g*, each of its ports being inclined in the same direction as the corresponding port *f'* of the corresponding sleeve *F'* and *F*². Steam is admitted from the inlet *g*² to the interior of the sleeve *G'* through the space between the two sleeves *F'* and *F*² and a central port *g*³ in the sleeve *G'*. The sleeve *G'* in this instance is permitted to reciprocate with the sleeves *F'* and *F*², in which it is held; but, as before, it is held from rotation in this instance by a pin *k* in the valve shell or casing *K'*, which engages a longitudinally-grooved lug *g*⁴ on the sleeve *G'*. The sleeve *H'*, which in this instance also is formed independently of the shell *K'*, for convenience in manufacture is provided with two obliquely-disposed ports *h*¹ and *h*², corresponding, respectively, with the ports *c*' and *c*² of the cylinder *C*. Exhaust-ports *h*³ and *h*⁴ communicate through a channel *h*⁵, having common exhaust-outlet *I'*.

The operation of the improved valve in the application thereof last described is substantially the same as in the construction first described herein. The steam from the inlet *g*² enters the inner sleeve *G'* through the space between the sleeves *F'* and *F*² and the port *g*³ and passes thence in the position of the parts represented in Fig. 4 through the port *g*, the port *f'* of the sleeve *F'*, and the port *h*¹ of the sleeve *H'* into the cylinder through the port *c*'. At the same time the exhaust-steam from the other end of the cylinder passes through the port *c*² in the cylinder-wall, the port *h*² in the sleeve *H'*, and the exhaust-channel *f*⁴ in the sleeve *F*² into the space between the end of the sleeve *F*² and the head of the shell, from which it escapes through the port *h*⁴ and the channel *h*⁵ to the outlet *I'*. The rotation of the sleeves *F'* and *F*² with respect to the ports *g* in the non-rotating sleeve *G'* and the ports *h*¹ and *h*² in the non-rotating sleeve *H'* insures the initial admission of steam to the cylinder at the same point with respect to the position of the piston therein, so that the lead remains the same under all conditions; but the longitudinal movements of the sleeves *F'* and *F*² under the action of the governor causes the cut-off to be varied with the varying speed of the governor. The regulation of lead, compression, and release may be effected independently in each case in the same manner as already described with respect to the construction shown in Figs. 1, 2, and 3.

It will be obvious that many changes in construction and relation of parts, particu-

larly with reference to different applications of the valve, may be made without departing from the spirit of the invention.

I claim as my invention—

- 5 1. A valve for steam-engines, comprising a sleeve provided with a port for the passage of steam, means to rotate said sleeve, means to move said sleeve longitudinally as the speed of the engine varies, a non-rotating sleeve within said rotating sleeve communicating with the steam-inlet and having a port to co-operate with the port in the rotating sleeve, and a sleeve outside of the rotating sleeve and having a port for the passage of steam 15 to the engine, substantially as described.
2. A valve for steam-engines, comprising a sleeve provided with a port for the passage of steam, means to rotate said sleeve, means to move said sleeve longitudinally as the speed 20 of the engine varies, a non-rotating sleeve within said rotating sleeve communicating with the steam-inlet and having a port to co-operate with the port in the rotating sleeve, and a sleeve outside of the rotating sleeve 25 and having a port for the passage of steam to and from the engine, said rotating sleeve also having an exhaust-channel in communication with the exhaust-outlet, substantially as described.
- 30 3. A valve for steam-engines, comprising a shaft, means to rotate said shaft, means to move said shaft longitudinally as the speed of the engine varies, a sleeve mounted upon said shaft to rotate and to move longitudinally therewith, a non-rotating sleeve within the first-named sleeve, communicating with the steam-inlet and having a port to co-operate with the port in the first-named sleeve, and a second non-rotating sleeve outside of the rotating sleeve and having a port for the passage of steam to the engine, substantially as described.
4. A valve for steam-engines, comprising a shaft, means to rotate said shaft, means to move said shaft longitudinally as the speed 45 of the engine varies, a non-rotating sleeve in communication with the steam-inlet and having a port, a sleeve outside of the first-named sleeve and secured to said shaft to move therewith, said sleeve having a port for the passage of steam and an exhaust-channel, and a third sleeve outside of the last-named sleeve and having a port for the passage of steam to and from the engine, substantially as described.
- 55 5. A valve for steam-engines, comprising a shell or casing, a sleeve fixed to said shell or casing, said sleeve having an inlet-port and a port for the passage of steam, a second sleeve mounted upon the first-named sleeve

and having a port, means to rotate said sleeve, and means to move said sleeve longitudinally as the speed of the engine varies, substantially as described.

6. A valve for steam-engines, comprising a shell or casing, a sleeve fixed to said shell or casing, said sleeve having an inlet-port and a port for the passage of steam, a second sleeve mounted upon the first-named sleeve, means to rotate the last-named sleeve, and means to move the last-named sleeve longitudinally as the speed of the engine varies, said shell or casing having an obliquely-disposed port to co-operate with the port in the rotating sleeve for the passage of steam to 75 the engine, substantially as described.

7. A valve for steam-engines, comprising a shell or casing having a port for the passage of steam to the engine, a sleeve fixed with relation to said shell or casing, said sleeve 80 having an inlet-port and a port for the passage of steam, a second sleeve mounted upon the first-named sleeve, means to rotate the last-named sleeve, and means to move said last-named sleeve longitudinally as the speed 85 of the engine varies, said last-named sleeve having a port to co-operate with the ports in the fixed sleeve and in the shell or casing, and having an exhaust-channel in communication with the exhaust-outlet to co-operate with the 90 port in said shell or casing, substantially as described.

8. A valve for steam-engines, comprising a shell or casing, a sleeve fixed to said shell or casing, said sleeve having an inlet and a port 95 for the passage of steam, a shaft mounted to rotate and to move longitudinally within said sleeve and a second sleeve mounted upon the first-named sleeve and connected to said shaft to move therewith, said second sleeve having 100 a port to co-operate with the port in the first-named sleeve, substantially as described.

9. A valve for steam-engines, comprising a shell or casing having an obliquely-disposed port, a sleeve fixed to said shell or casing, 105 said sleeve having an inlet and a port for the passage of steam, a shaft mounted to rotate and to move longitudinally within said sleeve, and a second sleeve interposed between the first-named sleeve and the shell or casing 110 and having a port for the passage of steam and connected to said shaft to move therewith, substantially as described.

This specification signed and witnessed this 11th day of November, A. D. 1902.

WILLIAM J. FRANCKE.
